UNITED STATES PATENT OFFICE.

PETER HENRY HOLTZ, OF DETROIT, MICHIGAN.

CARBURETER.

1,272,953.

Specification of Letters Patent. Patented July 16, 1918.

Application filed August 29, 1917. Serial No. 188,776.

To all whom it may concern:

Be it known that I, PETER HENRY HOLTZ, a citizen of the United States, and a resident of Detroit, in the county of Wayne 5 and State of Michigan, have invented a new and Improved Carbureter, of which the following is a full, clear, and exact description.

The object of the invention is to provide a carbureter suitable for the carburation of air, and it is characterized by means for imparting a rotary movement to the fuel and the air to better carbure the air.

To obtain the above result I provide a carbureter with a plurality of revoluble disks between which the fuel is admitted, and also air to be carbureted. The air helps to break up and to thin the oil between the disks.

Other characteristics of the invention will appear as the description proceeds.

In the accompanying drawings, forming part of the application, similar characters of reference indicate corresponding parts in all the views.

Figure 1 is an axial section through a carbureter embodying my invention;

Fig. 2 is a plan view of the cup into which the liquid hydrocarbon is fed;

Fig. 3 is a plan view of the surface of the disk facing the bottom of the cup;

Fig. 4 is a plan view of the upper surface of the disks between which the air is fed;

Fig. 5 is a plan view of the fanlike mixer disposed above the main air inlet of the carbureter; and

Fig. 6 is a top plan view of the cone disk located above the mixer.

Referring to the drawings, 7 is the lower section of the carbureter housing and 8 is the upper section which forms the dome. The two sections are connected to each other by a spacing ring 9 which has arms 9' extending to engage the dome and which provides an annular gap 10 between the two sections to form the main air inlet to the carbureter. The height of the gap may be varied by a ring 11 threaded on to the dome.

The ring 11 has a curved apron 12 which co-operates with the inwardly-directed curvature of the ring 9 so as to cause the air to flow toward the axial part of the dome. The lower part of section 7 of the housing accommodates the mechanism for va-

porizing the liquid hydrocarbons, and it comprises a series of superimposed disks of which 13 is in the shape of a shallow cup having a tubular stem 14 revolubly mounted in the bottom of section 7 to be coaxial with the housing. The projecting end of the tubular stem 14 is surrounded by a fuel-supply chamber 15 to which liquid fuel is supplied through a conduit 16. Apertures 17 are provided within the stem 14 which bring the same into communication with the chamber 15. Preferably the bottom of the cup tapers or slopes inwardly and it is provided with spiral grooves 18 which facilitate the movement of the fuel outwardly.

Positioned within the cup is a disk 19 the lower surface of which has also spiral grooves 18. In addition it is perforated to allow the oil to travel to the upper surface of the disk. The disk 19 has a tubular stem 20 coaxial with the stem 14. The annular space formed by the stems 14 and 20 serves as a conduit for the fuel to the cup. The annular space is closed at the lower end of the stem 14 by a member 21 carried by said stem and which serves as a bearing for the lower end of the stem 20. The stems 14 and 20 are each provided with a gear 22 and 23 respectively which are in mesh with gears 24 and 25 driven from independent shafts so as to revolve in opposite directions, the gears and shafts being indicated in dotted lines.

The cup 13 with the stem is displaceable along the axis by a spring 26 so that the clearance between the cup 13 and the disk 19 will vary with the speed of rotation and, therefore, the feed of fuel between the two adjusted. It is evident that the higher the centrifugal force the less will be the clearance between the cup and disk and, therefore, the more rapid will be the breaking up of the fuel passing therebetween.

To increase the disintegration of the liquid hydrocarbons I provide an additional pair of superimposing disks 27 each provided with perforations therethrough and annular grooves 28 on the upper face thereof. The two disks have coaxial tubular stems the annular space 30 between which serves as an air conduit to the space between said disks 27. The two stems at the lower end thereof are provided with gears 31 each in mesh with a corresponding gear 32, the two gears 32 revolving in opposite direc-

tions whereby the two disks 27 are revoluble oppositely. The air entering the passage 30 is driven outwardly by the centrifugal force and comes in contact with the hydrocarbon passing thereto through the perforations in the lower disk 27 and helps to break up this hydrocarbon and, in consequence, facilitates the evaporation of same. The frictional resistance of the disk surfaces also aids the evaporation of the liquid hydrocarbon.

The vapor passing through the upper disk 27 and near the margin of same is deflected by the ring 9 toward the central part of the dome, and as it passes to the dome it entrains the atmospheric air through the gap 10. The vapor and air are entrained by a fan-like mixer 33 which is in the shape of a shallow inverted cone the tubular stem of which projects through the tubular stem 29 of the upper disk 27 whereat a gear 34 is provided which meshes with a gear 35 for revolving said mixer in a direction opposite to the upper disk 27. The mixer, in addition to mixing the air with the vapor forces the mixture through a perforated shallow conical cup 36, the inner surface of which cup has annular grooves 37 and spiral slots 38. This cup has also a tubular stem passing through the stem of the mixer and provided at the lower end with a gear 39 which is in mesh with a gear 40 to be revolved in a direction opposite to the mixer. A similar cup 41 is provided within the cup 36. It has a stem 42 passing through the tubular stem of the cup 36. A gear 43 is secured to the lower end of the stem 42 and it meshes with a gear 44 whereby it is revolved in a direction opposite to the cup 36.

40 The dome 8 has a partition 45 which enters the cup 41 so as to present a substantially uniform clearance therebetween. Spring-held valves 46 are provided in the partition to open into the chamber 47 which is formed by the partition and the top of the dome. The outlet from the chamber is controlled by a butterfly valve 48 of the customary construction.

The pressure generated by the mixer 33 50 not only drives the mixture through the cups 36 and 41 but also through the valves 46 into the chamber, from where it is taken by the engine suction.

The invention is not confined to the particular details of construction shown and described as exemplifying the same but is capable of embodiment in various forms which will readily suggest themselves to one skilled in the art provided the modifications 60 fall within the scope of the claims.

I claim:

1. A carbureter comprising,—a two-part casing forming an air gap therebetween, means for varying the size of the gap, and 65 positively driven centrifugal means associated with one of said parts, means for supplying liquid hydrocarbon to the centrifugal means and whereby the same is vaporized in said part, and revoluble means in said other part of casing for drawing vapors 70 from the first part and air through the gap and forcing the two through said second part.

2. A carbureter comprising,—a two-part casing forming an air gap therebetween, a plurality of disks in one of said parts, means for revolving adjacent disks in opposite directions, means for supplying liquid hydrocarbon between said disks near the central part of same, and means associated 80 with the other part of the casing for forcing hydrocarbon vapors and air coming from the first part and draw air through the gap.

3. A carbureter comprising,—a two-part casing forming an air gap therebetween, a shallow cup revolvably mounted in one of said parts, a perforated disk revolvably mounted in the cup, means for supplying liquid hydrocarbon into the cup, said cup and disk having means on the facing surfaces for facilitating the flow toward the margin, means for revolving said cup and disk in opposite directions, a pair of perforated disks superimposing the first-mentioned disk and mounted to revolve, means 95 for revolving said disks in opposite directions, said disks having means whereby air may be drawn therebetween during the revolution of the disks, and means associated with said other part of casing for drawing 100 hydrocarbon vapors from said first part and air through the gap to force the two through said second part.

4. A carbureter comprising, a two-part casing forming an air gap therebetween, a shallow cup having a tubular stem revolvably mounted in one of said parts, a perforated disk within the cup and spaced from the bottom of same so as to form a clearance, a tubular stem for said disk passing through the stem of the cup and forming therewith an annular space, means for supplying liquid hydrocarbon into said space, means for revolving the cup and disk in opposite directions, the facing surfaces of said cup and disk having spiral grooves for facilitating the movement of the liquid toward the margin, a pair of perforated disks above the first-mentioned disk, said disks having tubular stems passing through the stem of the first mentioned disk, means for revolving said disks in opposite directions, one of the pair of disks in proximity of the first mentioned disk revolving in a direction opposite to said first mentioned disk, the stems of said pair of disks forming a clearance through which air may enter, the upper surfaces of said pair of disks having annular grooves, and means associated with the other part of casing for drawing the 130

hydrocarbon vapors from the first part and air through the gap, mixing the same, and forcing it through said second casing part.

5. A carbureter comprising, a two-part casing forming an air gap therebetween, a centrifuge in one of said parts, means for supplying liquid hydrocarbon to said centrifuge whereby the same is broken up into vapors, a mixer associated with the other part of casing for drawing the vapors from the first part and air through the gap, a cone-shaped cup revolubly mounted above the mixer, said cup having spiral slots through which the mixer forces the mixture, said cup having also annular grooves on the inner face thereof to increase resistance to the outward movement of the mixture through the rotation of the cup, a partition above said cup, and valves in said partition opening away from the cup.

6. A carbureter comprising,—a two-part casing forming an air gap therebetween, centrifugal means in one of said parts, means for supplying liquid hydrocarbon to the centrifugal means whereby the same is broken up into vapors, a fanlike mixer revolubly mounted in the other part of casing for drawing the vapors from the centrifugal means and air through the gap, a revoluble cup above the mixer having spiral slots through which the mixer is adapted to force the mixture, means for revolving said mixer and cup in opposite directions, means on the inner surface of the cup for increasing resistance to the outward flow therein, a similar cup superimposing the first-mentioned cup, means for revolving the same in a direction opposite to the first, a partition above the cups, and valves controlling the flow from said cups through said partition.

7. A carbureter comprising, a two-part casing forming an air gap therebetween, a centrifuge in one of said parts, means for supplying liquid hydrocarbon to the centrifuge to be vaporized by the centrifuge, a fanlike mixer revolubly mounted in the other part of casing to draw the vapors from the first part and the air through the cup, a plurality of interengaging cups mounted to revolve in said other part above the mixer, means for revolving said cups in opposite directions, means for revolving the fan-like mixer in a direction opposite to the cup above it, said cups having spiral slots through which the mixture is adapted to be forced by said mixer, annular grooves on the inner faces of said cups for increasing resistance to the outward flow of the mix-

ture, a partition above the cups, and valves in said partition checking the flow to said cups.

8. A carbureter comprising,—a two-part casing forming an air gap therebetween, means for varying the size of the gap, positively driven centrifugal means in one of said parts, means for supplying liquid hydrocarbon to the centrifugal means, a revoluble mixer associated with the other part for drawing the vapors from the first part and air through the gap, and valves above said mixer for checking the return flow.

9. A carbureter comprising,—a two-part casing forming an air gap therebetween, a plurality of disks in one of said parts, means for revolving adjacent disks in opposite directions, means for supplying liquid hydrocarbon between said disks near the central part of same, said disks having also means for drawing air therebetween, and a revoluble mixer in the other part of the casing for drawing the hydrocarbon vapors and air coming from the first part and air through the gap.

10. A carbureter comprising,—a two-part casing forming an air gap therebetween, a shallow cup having a tubular stem revolubly mounted in one of said parts, a perforated disk within the cup and spaced from the bottom of same so as to form a clearance, a spring engaging the stem of the cup whereby the clearance between the bottom of the cup and the perforated disk may be varied under the action of centrifugal force, a tubular stem from said perforated disk passing through the stem of the cup and forming therewith an annular space, means for supplying liquid hydrocarbon into said space, means for revolving the cup and disk in opposite directions, a pair of perforated disks spaced from one another and disposed in spaced relation above the first-mentioned disk, said pair of disks having interengaging tubular stems passing through the stem of the first-mentioned disk, said stems of said pair of disks forming an annular clearance for air to pass to said disks, means for revolving said disks in opposite directions, the disk in proximity of the first-mentioned disk revolving in a direction opposite to said first-mentioned disk, and a revoluble mixer in the other part of the casing for drawing the hydrocarbon vapors from the first part of the casing and air through the gap and force the mixture through said second part of casing.

PETER HENRY HOLTZ.
